Primary Examiner — Richard E Chilcot*(74) Attorney, Agent, or Firm* — Slayden Grubert Beard PLLC(57) **CLAIM**

The ornamental design a control unit for room automation, as shown and described.

DESCRIPTION

FIG. 1 is a front view of a control unit for room automation. FIG. 2 is a back view of a control unit for room automation. FIG. 3 is a top view of a control unit for room automation. FIG. 4 is a bottom view of a control unit for room automation.

FIG. 5 is a right view of a control unit for room automation. FIG. 6 is a left view of a control unit for room automation; and,

FIG. 7 is an isometric view of a control unit for room automation.

Broken lines are not part of the claimed design.

1 Claim, 7 Drawing Sheets(56)
